PRESSURE SWITCH

Willis H. Gille, St. Paul, Minn., assignor to Minneapolis-Honeywell Regulator Company, Minneapolis, Minn., a corporation of Delaware

Application May 5, 1944, Serial No. 534,189

24 Claims. (Cl. 200—81.5)

1

This invention relates to a condition responsive switch and more particularly to a fuel pressure switch which is adapted to be responsive to fuel pressure in a fuel line of an aircraft.

The pressure switch of this invention may be utilized in the fuel system of an aircraft, and which switch is actuated at predetermined fuel pressures by the fuel in a line of the fuel system.

When the pressure switch is moved to closed position by a predetermined fuel pressure in a fuel line, a relay means is energized for opening valve means so that fuel can be supplied to different heaters in an aircraft such as the cabin or cockpit heaters. If the pressure falls below a certain value in the fuel line, the fuel pressure switch moves to open position and the relay mechanism actuates the valve to closed position, thus shutting off the flow of fuel to the heaters. A break in the fuel line or a clogging in the fuel line would cause a fall in pressure below a predetermined or safe value and the fuel pressure switch would be opened. When the pressure of the fuel in the fuel line is below a certain value, the heaters would be damaged if fuel were fed to the heaters.

It is the purpose of this invention to utilize the novel switch of this invention in a fuel pressure system of an aircraft, which permits the feeding of fuel to the heaters at a predetermined high pressure value, and which prevents the feeding of fuel to the heaters when the pressure in the fuel line falls below a predetermined low value.

It is an object of this invention to provide a pressure switch in which the pressure sensing element is so arranged that there is a double seal formed between the fuel in the sensing element and the electrical contacts of the switch means to provide maximum safety of operation.

It is another object of this invention to provide a chamber surrounding a sensing bellows in which atmospheric or a pressure other than atmospheric pressure may be employed as a reference pressure in relation to the pressure employed in the sensing bellows.

It is another object of this invention to provide a first bellows for cooperating with a sealed chamber and the force resulting from pressure in a second bellows spaced in the chamber may be transmitted from said second bellows through the first bellows for actuating switching means on the outside of said chamber.

It is another object of this invention to provide a lever assembly which is associated with a pair of crossed reeds so that the lever assembly has a

2

movement in only one plane in order that the contacts of the switch remain in proper alignment for efficient and accurate operation of the switch.

5 It is still another object of this invention to provide a sensing bellows spaced in a sealed chamber so that differential pressures may be employed in the operation of the switching device.

It is still another object of this invention to 10 provide a flexible means for sealing an outlet in a chamber so that rocking movement may be transmitted from the chamber.

It is another object of this invention to provide 15 a lever assembly having rocking movement for transmitting motion from a sensing element so that a control device is quickly actuated.

It is a still further object of this invention to 20 utilize two pair of crossed reeds in a pressure switch device in order that a flexible and frictionless movement may be maintained between the sensing bellows and the switching means.

It is another object of this invention to provide 25 a switch which is arranged to cut in on increasing fuel pressure and to cut out on decreasing fuel pressure.

It is a still further object of the invention to 30 provide two pair of crossed reeds associated with a seal-off bellows for a chamber so that the seal-off bellows remains stable with changes in pressure in the chamber which houses the sensing bellows.

Other and further objects may become evident 35 from the following detailed description of the device.

For a complete understanding of my invention, 40 reference should be made to the accompanying drawings, in which

Figure 1 is an elevational view of the fuel pressure switch, the casing being in section and 45 parts being broken away;

Figure 2 is a vertical sectional view of the fuel pressure switch, parts being broken away;

Figure 3 is a sectional view taken on line 3—3 of Figure 2, in the direction of the arrows;

Figure 4 is an elevational view of the right side of Figure 1, parts being broken away.

Referring in detail to the fuel pressure switch, 50 10 is a base member for housing the pressure sensing element of this switch and comprises a lower portion 12 and a cap portion 14 having an enlarged section 15. Cap portion 14 is sealed to the lower portion 12 and forms a chamber 17. The base member 10 is preferably circular in shape.

55 The lower portion 12 of the base member 10

contains a flanged member 18 having a threaded passageway 20 formed therein which communicates with the interior of a sensing bellows 22 located in the chamber 17 formed by the portions 12 and 14 when in assembled relationship. The sensing bellows 22 is supported on and secured to the flanged sleeve member 18. Passageway 20 is adapted to be connected to a fuel line, not shown, of an aircraft, so that fuel pressure may be communicated to the sensing bellows 22. The lower portion 12 of the base member 10 also contains a second flanged member 24 having a threaded passageway 26 formed therein for communication with the chamber 17. The passage 24 is adapted to be connected to some pressure source, not shown, so that pressure may be supplied to the chamber 17 surrounding the sensing bellows 22. The pressure usually supplied to the chamber 17 is air pressure but other fluids may be employed such as fuel pressure or the like. The bellows 22 extends into the enlarged housing portion 15 in the cap portion 14 and a plunger 28 of the bellows 22 engages a notched portion 30 in a lever member 32.

Portion 34 of the lever 32 is substantially arcuate in shape (see Figure 3). There is an angular downwardly extending portion 35 at each end of the arcuate portion 34. A substantially right angular arm 36 extends from each of the downwardly extending portions 35 of the lever 32. The arms 36 merge into a portion 38 adjacent a post 40. The merged portion 38 of the lever 32 is secured to the post 40 which is associated with a seal-off bellows 42.

There is an opening in the cap portion 14 of the base member 10 communicating with the chamber 17, and the bellows 42 seals this opening in chamber 17 and separates chamber 17 from the electrical contacts of the switch means 64 spaced above the cap portion 14. The bellows 42 is open at its bottom for communicating with the chamber 17. The bellows 42 is positioned on the top of cap member 14 to the right of the bellows 22 as shown in Figure 2 of the drawings. Post 40 has a flanged portion 46 for securing a lever 48 to the top of the seal-off bellows 42. A plate 50 is carried between the lever 48 and the top of the bellows 42.

The left side of the lever 48 looking at Figure 2 has an arm of insulation material 52 secured thereto by rivet means. A contact arm 54 is secured by rivet means or the like to the insulation arm 52. An adjustable contact element 56 having a contact 58 at its upper end is screw threaded into an aperture in the contact arm 54. A contact arm 60 is spaced above the contact arm 54 and carries a mating contact 62 of the switch 64.

When there is a change in the fuel pressure in the sensing bellows 22, the lever 32, the post 40 of the seal-off bellows 42, lever 48, insulation arm 52, and contact arm 54 are actuated by the bellows 22 for opening and closing the switch 64 depending upon whether there is a fall or rise in the pressure in the sensing bellows 22.

There is an adjustable range spring 66 attached to the plate 50. This range spring normally biases the lever 48 in a counterclockwise direction.

The range spring 66 serves as an independent means for adjusting the values of the condition at which the switch 64 may be opened and closed.

Reeds 68 and 70 are associated with the plate 50 on the left side of the bellow 42 (see Figure 4). Each of the reeds 68 and 70 is formed of

a flat flexible spring-like material. The reed 68 is secured at its lower end to a block member 72 and has its other end secured to the under side of the plate 50. The reed 70 is likewise secured to the block member 72 at its lower end, while its upper end is secured to the under side of plate 50. The reed 70 is spaced slightly to the rear of the reed 68. The reeds 68 and 70 are crossed at substantially right angles between their points of attachment and are arranged edgewise at the point of crossing.

Reeds 74 and 76 are placed on the right side of the seal-off bellows 42 (see Figure 4), and have their upper and lower ends respectively secured to the plate 50 and a block member 73. The reeds 74 and 76 are of flat flexible spring-like material, and they are structurally arranged with respect to each other as are the reeds 68 and 70.

The reeds 68-70, and 74-76 function as flexible and frictionless pivots for the lever assembly 33 which comprises lever 32, post 40, lever 48, and arms 52 and 54. The fulcrum of each of the crossed reeds 68-70 and 74-76 is substantially at the point of crossing of the reeds. The lever assembly 33 pivots substantially about an axis determined by the intersections of the pair of crossed reeds. The crossed reeds 68-70, 74-76 are secured between the plate 50 and blocks 72 and 73 respectively in a taut condition. The crossed reeds being connected in a taut condition prevents upward and downward movement of the lever assembly, and also prevents lateral movement thereof, but allows a rocking movement of the lever assembly 33. This movement of the lever assembly in one plane maintains the contacts of the switch in proper alignment for efficient operation of the switch.

The operation of the switch in one application, as in an aircraft, is as follows: when fuel pressure at a predetermined value communicates through a pipe, not shown, and enters the passageway 20 at the bottom of the member 10 into the sensing bellows 22, the sensing bellows 22 is actuated upwardly and the plunger 28 thereof engages the lever 32 and force is transmitted from the lever 32 to the post 40 of the seal-off bellows 42. The force of the pressure is then transmitted from the post 40 to lever 48. The lever assembly 33 comprising the lever 32, post 40, lever 48, and arms 52 and 54 all move as one element and are pivoted substantially about an axis determined by the intersection of the pairs of crossed reeds 68-70 and 74-76 and the central transverse portion of bellows 42.

The bellows 22 actuates the left end of the lever 32 upwardly as seen in Figure 2. The lower end of the post 40 is moved to the left by the upward movement of the lever 32 while the upper end of the post 40 is moved to the right by the same motion, the post 40 pivoting substantially about an axis determined by the intersection of the pair of crossed reeds 68-70, and 74-76 at the central transverse portion of bellows 42. This pivotal movement of the post 40 causes the left end of the lever 48 to move upwardly carrying the connected arms 52 and 54 and the associated contact 58 so that the contact 58 engages the mating contact 62 on the arm 60, thereby closing the switch 64. This same pivotal movement results in a downward movement of the right end of the lever 48 and the plate 50 against the upward bias of the range spring 66.

The crossed reeds 68-70 and 74-76 are fastened at their upper ends to the plate 50 and at their lower ends to the blocks 72 and 73 respec-

tively, so that they hold down the upper end of the bellows 42, thus preventing the bellows 42 from moving upwardly due to the forces from the lever assembly 33 or from the pressure in the chamber 17.

The range spring 66 normally biases the plate 50 in an upwardly direction but upon actuation of the lever 32 upwardly by pressure acting on the inside of sensing bellows 22, the right end of lever 48 as seen in Figure 2 is moved downwardly but the force transmitted from bellows 22 through lever 32 and post 40 to the lever 48 must overcome the upwardly biasing force of the spring 66 before the switch 64 is actuated to closed position. The pressure in the sensing bellows 22 must also overcome the reference pressure in the chamber 17 before the switch 64 is actuated to closed position.

When the fuel pressure in the fuel line leading to the sensing bellows 22 falls below a predetermined value, the pressure in the sensing bellows 22 likewise falls. As a result, the end of the lever 32 adjacent the plunger 28 of the sensing bellows 22 is moved downwardly. The lever 32 now moves the lower end of the post 40 to the right as seen in Figure 2 while the upper end of the post 40 is moved to the left. The post 40 is caused to rock because it is pivoted on the axis formed by the intersection of the pairs of crossed reeds 68—70 and 74—76. This rocking movement of the post 40 moves the right end of the lever 48 upwardly and the left end of the lever 48 and its associated contact arm 54 downwardly; and arm 54 carries contact 58 from engagement with contact 62 on arm 60 and opens switch 64. The force of the biasing spring 66 which is upwardly on the right end of the lever 48 aids in pulling the opposite end of the lever 48 in a downwardly direction.

The positioning of the sensing element or bellows 22 in the chamber 17 of the member 10 necessitates means for transmitting the force acting on the sensing bellows 22 for operating the switch 64 spaced outside the chamber 17. The opening in the top of the cap portion 14 is sealed by the bellows 42 and its integral post element 40 extends into the chamber 17. The motion or force from the sensing bellows 22 is transmitted by lever 32 to the post 40 of the seal-off bellows 42. The movement of the post 40 actuates the lever 48 attached thereto and the associated arms 52 and 54. The bellows 42 which seals the chamber 17 being flexible permits motion to be transmitted from the sensing bellows 22 through the post 40 of the seal-off bellows 42 to the lever 48 so that the switch 64 may be actuated as is required in its association with the fuel system of an aircraft. The flexible seal-off bellows 42 being held downwardly by the crossed reeds 68—70 and 74—76 spaced on diametrically opposed sides thereof, permits the central transverse portion of the seal-off bellows 42 to be pivoted by the lever assembly 33 when actuated by the sensing bellows 22. That is, the lever assembly 33, when actuated by the sensing bellows 22, flexes the right and left sides of the bellows 42, as seen in Figure 2, upwardly and downwardly, respectively, and also downwardly and upwardly, respectively, thus pivoting the lever assembly 33 substantially about an axis passing through the central transverse portion of the bellows 42. The lever assembly 33 when actuated by the sensing bellows 22 flexes the upper ends of the reeds 70 and 76 upwardly and downwardly respectively, and also flexes the upper ends of reeds 68 and 74

downwardly and upwardly respectively, and the lever assembly 33 thus pivots about the axis determined by the intersection of the crossed reeds 68—70 and 74—76.

5 The bellows 42 also functions to seal the chamber 17 and different pressures may be supplied to the chamber 17 for contacting the outside of the sensing bellows 22 spaced in the chamber so that differential pressures may be employed in 10 the actuation of the switch device.

The spacing of the sensing element 22 in the chamber 17 provides a double seal means between the fuel in the sensing bellows 22 and the switch contacts of this device. The sensing bellows 22

15 acts as a first seal means for the fuel employed as the pressure actuating force, and if the bellows 22 should rupture, the fuel would then be discharged into the chamber 17, and the sealed chamber 17 would serve as a second seal means for sealing the fuel from the electrical contacts of the switch 64.

It will be readily apparent that in accordance with my invention, many changes may be made in the detailed construction and arrangement of the elements. It may be possible to use other means 25 for actuating the sensing bellows other than fuel pressure and for actuating the switch means in this light. The constructions set forth in this application are for illustrative purposes only, and 30 the invention is accordingly defined and limited only by the appended claims.

I claim as my invention:

1. In a switch of the class described comprising in combination, switching means, condition responsive means controlling the operation of the switching means, a sealed housing providing a chamber surrounding the condition responsive means so that differential pressures may be employed for actuating the switching means, the 35 housing having an opening, a bellows means for sealing the opening in the housing, a lever assembly, and crossed reed pivot means connected with the lever assembly, the lever assembly connected to the bellows through the opening in the housing, 40 the responsive means responsive to a change in the condition for causing rotation of the lever assembly about the crossed reed pivot means and the bellows for actuating said switching means.

2. In a switch of the class described comprising 50 in combination, switching means, condition responsive means for controlling the operation of the switching means, a housing comprising a chamber for surrounding the condition responsive means, the housing having an outlet, flexible 55 means sealing the outlet in the housing, a lever assembly associated with the flexible sealing means, a plurality of crossed reed pivots connected with the lever assembly, the condition responsive means causing rotation of the lever assembly 60 about the reed pivot means and the flexible sealing means between a predetermined range of values of the condition for opening and closing the switching means, and means for varying the 65 values of the condition at which the switching means is opened and closed by the condition responsive means.

3. In a device of the class described comprising in combination, a device to be actuated, a condition responsive means for controlling the operation of said device, resilient means opposing said condition responsive means, a lever assembly, and two pair of crossed reeds connected with the lever assembly, the condition responsive means upon a change in the condition causing rotation of the 75 lever assembly substantially about an axis deter-

mined by the intersection of the two pair of crossed reeds for actuating said device.

4. In a switch of the class described comprising in combination, switching means, a condition responsive means for controlling the operation of the switching means, a housing forming a sealed chamber which encloses the condition responsive means, the housing having an outlet means, a flexible means sealing the opening in the housing, a lever assembly extending through the outlet means of the housing and associated with the flexible sealing means, and reed pivot means connected with the lever assembly, the condition responsive means causing rotation of the lever assembly about the reed pivot means and the flexible sealing means between a predetermined range of values of the condition for opening and closing the switching means.

5. In a switch of the class described comprising in combination, switching means, a condition responsive means for controlling the operation of the switching means, a housing forming a sealed chamber which encloses the condition responsive means, the housing having an outlet means, a flexible means sealing the outlet means in the housing, a lever assembly extending through the outlet means of the housing and associated with the flexible sealing means, and two pair of spaced apart crossed reeds connected with the lever assembly, the condition responsive means causing rotation of the lever assembly substantially about an axis determined by the intersection of the two pair of cross reeds between a predetermined range of values of the condition for opening and closing the switching means.

6. In a device of the class described, comprising in combination, control means, a condition responsive means for controlling the operation of the control means, a chamber enclosing the condition responsive means, a seal-off bellows associated with the chamber, a lever assembly associated with the seal-off bellows, a plurality of spaced apart crossed reeds connected with the said lever assembly, the condition responsive means responsive to a change in the condition causing rotation of the lever assembly about the plurality of crossed reeds and the seal-off bellows for actuating the control means.

7. In a device of the class described, comprising in combination, control means, condition responsive means for controlling the operation of the control means, a housing forming a chamber enclosing the condition responsive means and separating the condition responsive means from the control means, a lever assembly, and two pair of spaced apart crossed reeds connected with said lever assembly, the condition responsive means responsive to a change in the condition for causing rotation of the lever assembly about the two pair of crossed reeds for actuating the control means.

8. In a control device, comprising in combination, control means, a condition responsive means for controlling the operation of the control means, a housing forming a chamber for enclosing the condition responsive means, the housing having outlet means, flexible means sealing the outlet means in the housing, a lever assembly associated with the flexible sealing means, and two pair of spaced apart crossed reeds connected with the lever assembly, the condition responsive means responsive to a change in the condition for causing rotation of the lever assembly about the two pair of spaced apart crossed reeds and

7
3
the flexible sealing means for actuating the control means.

9. In a switch of the class described comprising in combination, switching means, a condition responsive means for controlling the operation of the switching means, a housing forming a sealed chamber for enclosing the condition responsive means and separating the condition responsive means from the switching means, the housing having outlet means, a bellows sealing the outlet means, an actuator assembly comprising a first arm in the sealed chamber, a second arm spaced outside the chamber, and a portion connecting the first and second arms, the actuator assembly associated with the bellows, a plurality of spaced apart crossed reeds connected with the actuator assembly, the condition responsive means responsive to a change in the condition for causing rotation of the actuator assembly about the plurality of crossed reeds for actuating the switching means.

10. In a switch of the class described comprising in combination, switching means, fuel pressure responsive means for controlling the operation of the switching means, a housing comprising a chamber for sealing the fuel pressure responsive means from the switching means, the housing having outlet means, flexible bellows sealing the outlet means in the housing, the fuel pressure responsive means being a first seal means for the fuel pressure, the sealed chamber adapted to act as a second seal means for the fuel pressure, and rocking means comprising the flexible bellows means and two pair of spaced apart crossed reeds positioned adjacent the bellows means, the fuel pressure responsive means responsive to a change in the fuel pressure for moving the rocking means about an axis determined by the intersection of the two pair of crossed reeds for actuating the switching means.

11. In a switch of the class described comprising in combination, a switching means, a fuel pressure responsive means for controlling the operation of the switching means, a housing forming a sealed chamber for separating the fuel pressure responsive means from the switching means, the housing having an opening, bellows means sealing the opening the fuel pressure responsive means being a first seal means for the fuel pressure, the sealed chamber adapted to act as a second seal means for the fuel pressure, and lever means connecting the pressure responsive means with the switching means, the lever means connected with the bellows means, pivot means comprising two pair of crossed reeds positioned in diametrically opposed relation on the outside of the bellows and connected with the lever means, the axis of the pivot means passing through the central transverse portion of the bellows, the pressure responsive means responsive to a change in the fuel pressure for moving the lever means for actuating the switching means.

12. In a device of the class described comprising in combination, control means, condition responsive means controlling the operation of the control means, a housing providing a sealed chamber for enclosing the responsive means and separating the responsive means from the control means, the housing having an opening, bellows means sealing the opening in the housing, actuator means connecting the condition responsive means with the bellows means, and a plurality of spaced apart crossed reeds connected with said actuator means in such a manner for restraining upward movement of the bellows

means, the condition responsive means responsive to a change in the condition for causing rotation of the actuator means about the plurality of spaced apart crossed reeds and the bellows means for actuating the control means.

13. In a device of the class described, comprising in combination, control means, a pressure responsive means for controlling the operation of the control means, a housing forming a chamber enclosing the pressure responsive means and separating the pressure responsive means from the control means, the sealed housing having a reference pressure for regulating the operation of the pressure responsive means the housing having outlet means, flexible means sealing the outlet means in the housing, a lever assembly associated with the flexible sealing means, and two pair of spaced apart crossed reeds arranged adjacent the sealing means and connected to the lever assembly the condition responsive means responsive to a change in the condition for moving the lever assembly about the two pair of crossed reeds and flexible sealing means for actuating the control means.

14. In a control device, a body having a passage therein, an opening through said body communicating with said passage, pivot means, movable means pivotally mounted on said body in proximity to said opening, lever means extending through said opening and engaging said movable means, and bellows means arranged about said lever means and attached to said body and said lever in a manner to seal said opening against passage of fluid therethrough, said pivot means comprising crossed reeds arranged on diametrically opposite sides of said bellows in such a manner that the apparent axis of said crossed reeds extends through said bellows.

15. In a device of the class described, comprising in combination, a device to be actuated, a first chamber, a second chamber, the first chamber having outlet means communicating with the second chamber, bellows means sealing the outlet means communicating the two chambers, the device to be actuated arranged in the second chamber, pivot means comprising crossed reeds arranged on diametrically opposite sides of the bellows in such a manner that the apparent axis of said crossed reeds extend through said bellows means, condition responsive means arranged in the first chamber, and means connecting the condition responsive means with the bellows means, the condition responsive means responsive to a change in the condition for rocking the bellows about the pivot means for actuating the device.

16. In a device of the class described, comprising in combination, a control device, a first chamber, a second chamber, the first chamber having outlet means communicating with the second chamber, bellows means arranged in the second chamber and sealing the outlet means communicating the two chambers, pressure responsive means arranged in said first chamber, lever means connecting the pressure responsive means with the sealing bellows, and pivot means comprising crossed reeds arranged on diametrically opposite sides of the bellows in such a manner that the apparent axis of said crossed reeds extends through said bellows, the pivot means connected to said lever means, the first chamber providing means so that differential pressures may be employed in the operation of the control device, the pressure means responsive to changes in pressure for rocking the lever means about the pivot

and sealing bellows for controlling the operation of the control device.

17. In a device of the class described, comprising in combination, means enclosing a space, said 5 enclosing means having an opening, means extending through said opening, means operated by said extending means, means actuating said extending means, means sealing said opening about said extending means, and pivot means for said 10 extending means, said pivot means comprising oppositely arranged crossed reeds, the axis of said pivotal means passing through said sealing means.

18. In a device of the class described, comprising in combination, means enclosing a space, said 15 enclosing means having an opening, means extending through said opening, means operated by said extending means, means actuating said extending means, bellows means sealing said opening about said extending means, and pivot means for said 20 extending means, said pivot means comprising oppositely arranged crossed reeds, the axis of said pivotal means passing through bellows sealing means.

19. In a device of the class described, comprising in combination, means enclosing a space, said 25 enclosing means having an opening, means extending through said opening, means operated by said extending means, means actuating said extending means, bellows means sealing said opening about said extending means, and pivot means for said 30 extending means, said pivot means comprising crossed reeds arranged in diametrically opposed relation on the outside of the 35 bellows means, the axis of said pivot means passing through said bellows sealing means.

20. In a switch of the class described, comprising in combination, switching means, fuel pressure responsive means controlling the operation 40 of the switching means, a housing comprising a chamber for sealing the fuel pressure responsive means from the switching means, the housing having outlet means, a flexible bellows sealing the outlet means from the housing, fuel pressure responsive means being a first seal means for the fuel pressure, the sealed chamber adapted to act as a second seal means for the fuel pressure, actuating means associated with the fuel pressure responsive means, the flexible sealing bellows 45 means and the switching means, flexible pivot means comprising two pair of spaced apart crossed reeds positioned adjacent the bellows means and connected with the actuator means, the fuel pressure responsive means responsive to 50 changes in the fuel pressure for rocking the actuator assembly about an axis determined by the intersection of the two pair of crossed reeds for actuating the switching means.

21. In a switch of the class described, comprising 55 in combination, switching means, fuel pressure responsive means controlling the operation of the switching means, a housing comprising a chamber for sealing the fuel pressure responsive means from the switching means, the housing 60 having outlet means, a flexible bellows sealing the outlet means from the housing, the fuel pressure responsive means being a first seal means for the fuel pressure, the sealed chamber adapted to act as a second seal means for the fuel pressure, and 65 rocking means comprising the flexible bellows and a plurality of spaced apart crossed reeds positioned adjacent the bellows means, the fuel pressure responsive means responsive to changes in the fuel pressure for moving the rocking means 70 about an axis determined by the intersecting of 75

11

the plurality of spaced apart crossed reeds for actuating the switching means.

22. In a device of the class described, a device to be actuated, force producing condition responsive means for controlling the operation of said device, a lever, and a pair of crossed reeds connected to said lever, the condition responsive means upon a change in the condition causing rotation of said lever substantially about an axis determined by the intersection of said crossed reeds for actuating said device, the force produced by said condition responsive means placing said reeds in tension. 10

23. In a device of the class described, a device to be actuated, force producing condition responsive means for controlling the operation of said device, resilient means opposing said condition responsive means, a lever, and a pair of crossed reeds connected to said lever, the condition responsive means upon a change in the condition causing rotation of said lever substantially about an axis determined by the intersection of said crossed reeds for actuating said device, the force produced by said condition responsive means and said resilient means placing said reeds in tension. 15

24. In a device of the class described, a device to be actuated, force producing condition responsive means upon a change in the condition causing rotation of said lever substantially about an axis determined by the intersection of said crossed reeds for actuating said device, the force produced by said condition responsive means and said resilient means placing said reeds in tension. 20

25. In a device of the class described, a device to be actuated, force producing condition responsive means upon a change in the condition causing rotation of said lever substantially about an axis determined by the intersection of said crossed reeds for actuating said device, the force produced by said condition responsive means and said resilient means placing said reeds in tension. 25

12

sive means for controlling the operation of said device, resilient means opposing said condition responsive means, a lever, and a pair of crossed reeds connected to said lever intermediate said condition responsive means and said resilient means, the condition responsive means upon a change in the condition causing rotation of said lever substantially about an axis determined by the intersection of said crossed reeds for actuating said device, the force produced by said condition responsive means and said resilient means placing said reeds in tension.
